AXEL W. CARLSON, OF WORCESTER, MASSACHUSETTS, ASSIGNOR TO CARLING TURBINE BLOWER CO., OF WORCESTER, MASSACHUSETTS, A CORPORATION OF MASSACHUSETTS.

METHOD AND MEANS FOR MAKING TURBINE-ROTORS.

1,311,109.

Specification of Letters Patent.

Patented July 22, 1919.

Application filed December 19, 1918. Serial No. 267,540.

To all whom it may concern:

Be it known that I, AXEL W. CARLSON, a citizen of the United States, residing at Worcester, in the county of Worcester and 5 State of Massachusetts, have invented certain new and useful Improvements in Methods and Means for Making Turbine-Rotors, of which the following is a specification.

My present invention relates to certain 10 features of novelty in the method of producing turbine rotors having a plurality of impact stages or completely assembled rings of blades, vanes or buckets; also to means peculiarly adapted to facilitate the carrying 15 out of the method for the manufacture of such rotors; the objects being to render the production or making of turbine rotors of the characters specified; more convenient, simple and economical in manufacture; and 20 to produce better, more accurate and efficient rotors for use in elastic fluid turbine engines.

Another object is to attain a method whereby the series of blades are primarily 25 assembled and secured in their regular order and relation, together with outer and inner concentric circular bands; thereby forming a complete practically non-distortable blading annulus, that can be handled, transported and treated in more or less careless 30 or rough manner without causing injurious derangement therein, but maintaining its prepared condition ready at any time for use as a conveniently placeable unit, in subsequent steps of the manufacture.

Minor objects and features of invention will appear set forth in the following detailed description, and as illustrated in the accompanying drawings, wherein Figure 1 40 represents a plan view of improved means adapted for employment in the method of making turbine rotors in accordance with my invention; portions being shown broken away the better to reveal the structure. Fig. 45 2 is a cross section of the same at line X X on Fig. 1. Fig. 3 represents (on smaller scale) a plan view of a finished rotor having two stages or sets of blades or vanes; portions being broken away to reveal the under 50 set of blades. Fig. 4 represents a cross section through the side of the core-box, clamp-plates and intermediate separator element; showing said parts as relatively positioned, but slightly away from each other. Fig. 5 55 represents a separate plan view of the intermediate separator annulus, with dot-and-

dash lines indicating the manner of releasing the sections from between the dual rows of blade shanks. Fig. 6 is a cross-section of the separator annulus taken on line Y Y on 60 Fig. 5. Fig. 7 is a separate view of the blading annulus, or series of blades and circular bands, as assembled and secured in their complete order and relation preparatory to their incorporation with core-forming means. Fig. 8 is a detached view of one of the blades, and one with cross-sections of the inclosing bands with which the blades are assembled and secured, and Fig. 9 is a cross section view through one side of the 70 turbine engine, showing the relation of the plural staged blading to the engine casing and intervening stationary sector of reversed blades.

In the manufacture of turbine rotors of 75 the character referred to, the blades or vanes 5 are individually formed with a reduced longitudinally extended shank 6 at the inner end, and a short projecting stud or tenon 7 at the outer end; the body of the blade being of the usual concavo-convex cross-section form. The effective working length of the blade is made to correspond with the desired radial dimension of the particular stage or circular row of blading in which 85 it is to be used, since the respective stages may be of different widths.

In practice, as employed in turbine engines, the parts may be relatively disposed substantially as indicated in Fig. 9, wherein 90 C denotes engine casing; e the steam injecting nozzle or passage; 4 the rim of the rotor; a the first stage or row of blades; b the second stage or row of blades; the blades of both stages being rigidly fixed, by casting, 95 in the rotor rim.

D indicates the stationary sector of 100 reversely positioned blades d disposed inwardly between the two stages a and b, and supported in the sector body D that is firmly secured within the engine casing C.

The sector-blades d serve to direct the flow of steam or elastic fluid, after passing the first stage, to impinge in proper direction against the blades of the second stage. 105

According to my improved method I primarily provide two complete circular bands 2 and 3 of comparatively thin flat metal, preferably rolled bronze or hard-drawn brass, and dimensioned for concentric disposal with intervening area equal to the length of the blades 5. Each of said bands 110

is perforated with a series of holes therethrough, numerically corresponding to the series of blades, and shaped to approximately fit their projecting ends; the openings in the inner band to receive the shanks 6, and those of the outer band to fit the tenons 7.

- As a permanent ring or annulus, the full series of blades 5 and bands 2 and 3 are 75
 10 paratively assembled with the shank 6 of the blades extending through and projecting inward within the inner band 3, as at 20, and with the outer end tenons 7 passed through and secured in the openings of the 80
 15 outer band 2, preferably by riveting down their outer ends; which can be readily effected by the aid of a suitable form or jig for temporarily supporting the members while being arranged and secured together. 85
 20 By this method of primary assembling the series of blades, with an outer and inner circular band, both ends of the blades are confined against displacement and there is produced a complete dual rimmed annulus 90
 25 of blading, which is comparatively firm laterally and in circle, and can be handled, transported and treated without extreme care in the works, since the particular structure of this prepared blading-
 30 annulus is peculiarly adapted to resist disarrangement or distortion of its parts, and for maintaining, for any length of time, its primal condition as a conveniently placeable unit of the character shown in Fig. 7. 95
 35 For preparing the thus assembled series of blading for having the body-wheel cast in connection therewith, the main portion of the blades and outer band are embedded in a protecting annulus of core material 100
 40 formed thereon, substantially as hereinafter explained. For this purpose I provide a circular core-box 10 having a circular shoulder 11, and adapted for supporting the annular bottom clamp-plate 12 concentric 105
 45 therewith; said clamp-plate being peripherally of a size that fits the inside circle of the inner band 3. A substantially similar upper clamp-plate 13 is also arranged in the box 10. Said clamp-plates are provided 110
 50 with spaces 5^a and 5^b for the reception of the shanks 6 of the blades. 115

A separator element 15 is arranged intermediate the clamp-plates 12 and 13. Said separator element consists of a flat annulus 120
 55 composed of segments or sections separably joined, so that its sections can be retracted or moved backward within the area of its circle. As illustrated in Fig. 5, it consists of four segments, two of which *n n* are at 125
 60 their lower ends abuttingly joined or matched to the fourth, *o*, by joints *r* that permit a swinging or rolling action, while their other ends are formed with oppositely facing approximately straight surfaces *s*, 130
 65 which may be parallel or slightly inclined,

and between which the first segment *m*, which is formed with approximately straight end-faces *s¹*, is arranged to match, so as to brace the segments *n n* apart for keeping the separator extended, or to be drawn back, 70
 as indicated by dotted lines *m²*, and removed; after which the second segments *n n* can be swung inward as indicated at *n²*; then the fourth segment *o* can be drawn back. Each of the segmental sections is provided with a loop *p* or equivalent means for its convenient retraction. 75

The joint faces of the segments are best made with a narrow dressed contact surface at the periphery of the annulus, and relieved from contact at a short distance back therefrom; thus affording a perfect rigidity of the circle, but permitting ready release of the sections without disturbing the surrounding core. 85

The peripheral edge of the separator element may be perpendicular to its plane, or inclined to conform to any offset between the edges of the clamp-plates below and above it. 90

Suitable bolts 16 are arranged through the parts 13 and 15 and screw threaded into the bottom plate 12 for clamping them firmly upon the shanks 6 of the blades. 95

The clamp-plates are made of such circumferential dimension as will approximately fit within the inner bands of the assembled blading-annulus. 100

After the series of blades 5 is assembled and secured with the bands 2 and 3, as a unit, the annulus is placed upon the lower clamp-plate 12 with the inwardly projecting shanks 6 resting in the space or spaces 5^a and the inner band 3 embracing the periphery of said plate. The separator ring 15 is placed upon the shanks, in annular form, with its peripheral edge approximately aligned with the inner band, then another or second stage annulus of assembled blades and bands, as a unit, is placed upon the top of the separator element with its inwardly projecting shanks 6 resting thereon, as at 20, Fig. 1. After which the upper clamp-plate 13 is arranged in inverted relation upon this second row of shanks, and the several plates 13, 15 and 12 are forced together by the bolts 16, thus firmly clamping the plural sets of shanks 6 in position and retaining the several dual-banded series of assembled blades in their proper stage relation. 110

When thus clamped and supported the blading annulus and clamp devices are arranged within the circular core-box 10; then the space 19 surrounding the clamp-plates 12 and bands, is packed full with core material 17, closely embedding the blades 5 and outer band 2, and filling in against the separator 15 and exterior surface of the inner bands 3, thereby forming a complete annu- 130

lar core 17 containing the plurality of sets of blades securely held in place therein in their proper determined relation. This core is then baked, or treated for hardening in 5 usual manner for cores. The clamping device, together with the annular core containing the inclosed blading and bands, is subsequently taken from the core-box 10, the bolts 16 released, and the upper and 10 lower clamp-plates removed.

The intermediate separator 15 can be released and taken from between the two rows of inwardly projecting shanks, by first drawing the segment or section *m* backward 15 within the circle between the opposite joint surfaces *S*, as indicated at *m*² on Fig. 5; then swinging inward the two side sections *n* *n*, as indicated by dot-and-dash lines *n*², and then drawing inward the remaining section *o*. Thus the several parts 20 of the separator can be readily taken from the interior of the circle of shanks, in a plurality staged blade assemblage, leaving the inclosing core intact with the shanks 25 projecting inward therefrom, as at 20, and faced with the inner bands 3.

This annular core containing the plurality of rings of band-connected blades, is then placed in a suitably shaped wheel-mold, formed in molding sand, and the body-wheel 14 cast therein of molten metal; (preferably phosphor-bronze) the metal in the rim portion 4 of the wheel uniting with the inner bands 3, and solidly embedding the 30 plural rows of blade-shanks 5, which project inward through said bands, thus making an integral structure. The rotor-casting is then removed from the mold, and the core material freed from the blading, which is 35 left with clear inter-spacings without requiring difficult cleaning out between the 40 blades.

The sides of the rotor and edges of its rim 4 are finally dressed or turned off to 45 the size and surface finish required for use in the turbine engine.

In the present illustration the rotor is shown as made with two stages or circular rows of blades assembled between inner and 50 outer bands 2 and 3 as described; but it will be understood that the plurality construction may include a greater number of 55 rows of blades incorporated with a single rim or casting, in the same manner and by substantially the same method and means herein described.

In practice the plural staged rotor, as employed in the turbine engine, is associated with a sector *D* of stationary inverted blades 60 *d*, and it may be noted that by my method and means a rotor can be readily and economically made which will run with true accuracy therewith and give high efficiency of service.

65 The stationary reversing sectors *D* may be

made by substantially the same method above described; that is, by primarily assembling and securing the series of blades in their determined order with circular outer and inner bands; inclosing the blades in an 70 annular core and casting the body thereon; except that the shanks of the blades *d* are projected outward through the outer band instead of inward through the inner band; and the casting of the body or rim *D* is 75 made upon the exterior instead of the interior of the circular annulus, the latter being cut into sectors after the casting is completed.

By primarily assembling and securing the 80 series of blades with the outer and inner bands, as a unitary annulus, much labor and annoyance is obviated in the subsequent handling and placement of the same for casting, insuring greater accuracy in the 85 casting operations; and clean unobstructed passages between the blades are attained.

The bands 3 being of quite thin metal and backed by core material, instead of a metal support, the liability of chilling the molten 90 metal when casting the body is obviated, and a more perfect integration of the wheel-rim and blading annulus results.

What I claim is—

1. The method of making molds for turbine rotors, which consists in primarily forming a blading annulus by assembling the series of blades between circular concentrically disposed outer and inner perforated bands, the shank of the blades extending through and projecting at the interior of the inner band; securing the outer ends of the blades in the outer band, supporting said blading annulus in a circular clamping device, placing the same within a 95 surrounding core-box and inclosing the blades and outer band with core material, baking said core material thereon, then removing the clamping device leaving the face 100 of the band and projecting shank exposed, placing the circular core and inclosed blade annulus in a suitably formed wheel-mold, and casting the body of the rotor therein, integrant with the inner band and solidly 105 embedding the inwardly projecting shanks 110 of the blades.

2. The improvement in the method of making rotors for elastic fluid turbines, which consists in primarily forming a complete blading annulus, by assembling the series of blades in their regular order with an outer and inner concentrically disposed perforated band of thin flat-rolled metal, their outer ends secured in the outer band and 115 their extended shanks passed through the inner band and projecting within the circle thereof, substantially as set forth.

3. In a method of making turbine rotors; preparatively assembling the complete series of blades, having outward and inward shoul- 120 125 130

ders and longitudinally projecting reduced ends, with a plurality of perforated concentric blade-connecting bands by which both ends of said blades are supported in their determined relative order, endwise embraced between the bands, said assembled bands and blades constituting a dual-rimmed transportable unitary annulus, with the shanks of the blades projecting therefrom.

10 4. In the method in making rotors for elastic-fluid turbine motors, the improvement which consists in primarily forming a preparatory blading annulus, by assembling a full series of blades in their regular order 15 with serially perforated outer and inner circular bands of thin flat-rolled metal, with their inner reduced shanks extending through and projecting within the circle of the inner band, their outer ends extending 20 through and externally riveted upon the outer band.

5. In the manufacturing of turbine rotors, the method of uniting the series of blades in a blading-annulus, which consists in assembling blades having extended shanks and short tenons at their respective ends in radially disposed order between an outer and inner circular band of thin flat metal having corresponding perforations therein, projecting the shanks through one of said bands and permanently securing the tenons in the perforations of the other band by riveting down the ends of the tenons, said parts being combined as a dual-banded non-distortable annulus, for the purpose set forth.

6. The method, in making plural-staged rotors for turbine engines; which consists in assembling and confining, in the form of an annulus, series of radially disposed blades arranged in determined order between outer and inner perforated circular bands, with their shanks projecting through said inner band, supporting a plurality of such assembled blade series by their shanks, between 40 upper and lower clamp-plates and an intermediate separator annulus composed of inwardly withdrawable segments, forming an incasing core about the plural series of blades, then releasing the clamp-plates and 45 drawing the segments of the intermediate separator-annulus inward within the circle, substantially as set forth.

7. The method of making molds for turbine rotors, which consists in preparatively arranging the series of blades in their proper relative order, with an outer perforated band and an inner perforated band as a unitary annulus or ring, by projecting their shanks through the openings in the inner 55 band and fixedly securing their opposite end tenons in the openings in the outer band, su-

perposing a plurality of such circular arranged blade rings with their inwardly projecting shanks held between peripherally circular clamp-plates; and a segmentally sectioned intermediate separator annulus, then forming a unitary annular core upon and inclosing said plurality of blading rings, detaching the clamp-plates therefrom and releasing the separator by successively withdrawing its individual sections inward within the circle.

8. The method of making plural staged turbine rotors; means for supporting a plurality of rings of completely assembled turbine blades, comprising upper and lower annular clamp-plates and an intermediate annulus disposed between said clamp-plates, composed of segmental sections adapted to be individually released from the circumferential circle thereof, and bolts arranged through said clamp-plates and separator annulus and adapted for retaining the segments in position and for clamping said plates together.

9. An apparatus for making turbine rotors, comprising upper and lower annular clamp-plates having spaces for receiving the shanks of an annularly arranged series of turbine blades and concentric bands securing said blades in upper and lower annular assembled stages, an intermediate separator annulus composed of separable segmental sections individually retractable within its circle, one of said sections adapted for retaining the others in annular position and for releasing the same when withdrawn, means for withdrawing the segmental sections, a core-box affording an annular core-forming space about the periphery of said clamp-plates and separator annulus, means for retaining the clamp-plates concentric with the core-box, and means for clamping the several plates together.

10. In an apparatus for the purpose described, in combination with upper and lower clamp-plates, a circumferentially circular separator element, composed of a plurality of separable adjacently abutting segmental sections, two of which are provided with oppositely disposed approximately straight joint faces, an intermatching segmental section having end faces adapted to slide between the joint faces of said two sections, and means whereby said intermatching section can be withdrawn inward within the circle in the plane of the separator element.

Witness my hand this 16th day of December, 1918.

AXEL W. CARLSON.
